UNITED STATES PATENT OFFICE.

CALEB R. AYER, OF BOSTON, AND GEORGE A. AYER, OF WORCESTER,
MASSACHUSETTS.

STEAM BOILER AND FURNACE.

SPECIFICATION forming part of Letters Patent No. 498,606, dated May 30, 1893.

Application filed July 30, 1892. Serial No. 441,645. (No model.)

To all whom it may concern:

Be it known that we, CALEB R. AYER, of Boston, in the county of Suffolk, and GEORGE A. AYER, of Worcester, in the county of Worcester, State of Massachusetts, have jointly invented certain new and useful Improvements 5 in Steam Boilers and Furnaces, of which the following, taken in connection with the accompanying drawings, is a specification.

This invention relates to steam boilers of the downward-draft water-tube type, the fire box having its draft opening above the grate and the volatile products of combustion being deflected downwardly and all caused to 10 pass through the incandescent mass of fuel on the grate where they are utilized as fuel or consumed in the combustion chamber beneath the grate. The highly heated current then travels by a circuitous path among a 15 multiplicity of water-tubes connected at their ends to water-containing walls diverging as they rise and crowned by steam drums.

Our present invention consists in the combination with a water grate and a transverse 20 water box with which all the tubes of said grate connect at the inner end of the fire-box, of a series of water-supply pipes below the 25 front water wall obliquely upward through the combustion chamber to and into said transverse water-box, so as to supply therefrom water to the grate tubes which rise thence 30 and connect with said water wall.

Our invention further includes water-containing front and rear walls for the water 35 tubes, such walls being continuous from side to side of the boiler, each diverging from the bottom, upwardly, for complete clearance, and terminating in a transverse steam drum. It also embraces such continuous walls and 40 terminal steam drums riveted longitudinally together at their edges and suitably stayed, in combination with inclined water tubes connecting said walls.

In the drawings, Figure 1 is a longitudinal 45 vertical section through our improved boiler, and Fig. 2 is a front elevation thereof.

A is the water wall forming the front of the fire box, B B the feed doors and C the ash 50 door therein.

D is a transverse water-leg, which forms

the closed inner end of the fuel chamber and deflects downwardly the entire caloric current. This water leg or band extends transversely from side wall to side wall of the boiler, and communicates with the water-spaces 55 therein.

The grate is composed of parallel water tubes E E E extending obliquely downward from the water wall A to the water-box F, 60 which is made independent of the side walls of the boiler and lies adjacent to and parallel with the lower part of the water-leg D. Water for circulation through the grate tubes E is supplied to this water box through the enlarged oblique supply pipes G which descend 65 from said box and enter the lower part of the front wall A of the fire box at each side of the ash-pit door C.

H is the main feed-water inlet pipe, and 70 I I two branch pipes running therefrom through the combustion chamber to supply the fire box wall and the grate fed therefrom. By this construction water is drawn from the coolest part, where it is supplied from the 75 inlet pipe and is heated as it moves through the combustion chamber and rises through the pipes G, by the intense current of combustible gases descending from the grate, and by the exceedingly high temperature of the 80 combustion chamber beneath the grate. It is further heated in the transverse water box, and in the grate tubes on which the fuel rests, the water continually rising and having free circulation as it advances. 85

The body of the boiler is filled in with a multiplicity of inclined water tubes J among which the caloric current travels in a circuitous path as indicated by the arrows, it being shown as deflected by a fire brick wall 90 K in rear of the water leg D, by inclined fire-brick slabs L, and by a depending water leg M in the upper portion of the boiler, toward the rear. The ends of the several water tubes J enter the inner plates of the front 95 and rear water walls N, O, these plates being parallel to each other and at right angles to the tubes J, and hence somewhat inclined as compared with the vertical front plate N of the front wall,—the plates of each wall diverging as they rise to afford abundant clearance. The outer plate of the rear wall O is 100

thus still more inclined from a vertical position as seen in Fig. 1. The end walls N, O, are each continuous from side to side of the boiler, so that all the pipes J open into both 5 of these walls. The pipes will be screwed or expanded into the inner plates, while the outer plates will have, opposite thereto, screw caps P to afford access to each tube. Similar caps for the supply pipes G, are shown in Fig. 10 2. The top of each wall N, O, is crowned by a nearly cylindrical steam drum Q to which their front and rear plates are firmly riveted, stay strips R being provided, at intervals 15 from front to rear to support the parts against the pressure, as indicated in Fig. 1. Where the bottom portion of the drum is apertured but not removed the metal remaining forms a partial stay. Each drum is furnished 20 with a man-hole in its end or elsewhere. A series of enlarged horizontal pipes S connects the upper portion of the front and rear walls N, O, to equalize the pressure and for 25 circulating pipes.

The front wall N being distinct from the fire-box wall A, we provide for communication 25 between them by water-pipes T rising from the upper part of the wall A and entering the wall N above it, to give free circulation for the water rising from the grate. 30 These pipes T are shown in Fig. 2 at each side only but they may be placed, at intervals, on the front also, if preferred. These pipes will be suitably sheathed to prevent cooling of the water or condensation of the steam therein. 35 Water is supplied to the rear wall O, from the transverse main pipe H, through several upright tubes U as indicated in Fig. 1.

We claim as our joint invention—

1. In a downward draft boiler furnace, the 40 upright water-leg D communicating with the

side walls of the boiler at the inner end of the fire-box, the transverse water-box F adjacent to but independent of said water leg and side walls, and the water grate E connecting the water box F with the front water wall 45 A, in combination with the water supply pipes G, extending from the water box F obliquely downward and communicating with the lower portion of the front water wall, through which wall access is had to the interior of said tubes and box, substantially as set forth.

2. In a downward-draft water-tube boiler, the combination with a multiplicity of inclined water-tubes among which the caloric 55 current is caused to pass, of front and rear water-containing walls extending continuously from side to side of the boiler, formed with parallel inner plates with which the ends of said water tubes engage, and with outer 60 plates diverging upwardly in opposite directions from said parallel inner plates, substantially as and for the purpose set forth.

3. In a downward-draft water-tube boiler, the combination with a multiplicity of inclined water-tubes and with front and rear water-walls having their respective outer and inner plates upwardly diverging, of steam drums riveted longitudinally to the upper edges of such diverging plates and suitably 70 stayed, substantially as set forth.

In testimony whereof we have signed our names to this specification, in the presence of two subscribing witnesses, on this 5th day of July, A. D. 1892.

CALEB R. AYER.
GEORGE A. AYER.
